COAXIAL CONNECTOR AND SWITCH
COMBINATION

Robert G. White, Portland, Oreg., assignor to Tektronix, Inc., Beaverton, Oreg., a corporation of Oregon
Filed Apr. 26, 1962, Ser. No. 190,499
9 Claims. (Cl. 200—153)

The present invention relates generally to electrical connectors and switches and in particular to a coaxial connector and switch combination for connecting a coaxial cable transmission line to an electrical apparatus in a plurality of different ways depending upon the position of such switch.

The electrical connector and switch device of the present invention is especially useful as the input terminal for the vertical signal preamplifier of a cathode ray oscilloscope. This coaxial cable connector and switch device may be used to change the electrical connections of such vertical signal input terminal between two or three switch positions including an A.C. position, a D.C. position and a ground position. In the A.C. switch position the inner conductor of the coaxial cable connector is connected through a direct current blocking capacitor to the vertical signal preamplifier. In the D.C. position such inner conductor is directly connected to the vertical preamplifier by short-circuiting the blocking capacitor, while in the ground position the inner conductor is disconnected and the vertical preamplifier is connected to ground.

The switch portion of the electrical connector and switch device of the present invention is made integral with such connector and has its switch contacts positioned within such connector in order to reduce the capacitance and the inductance of such device so that the input signal supplied by the coaxial cable is transmitted through such device without appreciable distortion of such signal. Another advantage of this coaxial cable connector and switch device is its simple, inexpensive and rugged construction. The combining of a coaxial cable connector and switch into an integral device also results in less wiring time and fewer soldered connections along with shorter lead lengths to provide a more reliable device with better high frequency characteristics. Still another advantage is a saving of mounting space on the control panel of the oscilloscope since formerly the switch and coaxial connector were mounted separately in spaced positions on such panel.

Briefly, one embodiment of the electrical connector and switch device of the present invention includes a connector member in the form of a coaxial cable transmission line section having an inner signal-carrying conductor coaxially mounted inside an outer shield conductor and insulated therefrom with one end of each of such conductors adapted to be connected to a coaxial cable transmission line. A rotary switch is supported by such connector member including a rotary switch contact mounted inside the outer conductor adjacent the other end of such outer conductor for rotation on the inner conductor between a plurality of different switch positions while the rotary contact engages such inner conductor. A stationary switch member including at least one stationary switch contact is also mounted inside the outer conductor of the connector member so that such stationary contact is insulatingly spaced from the inner conductor and the outer conductor and is positioned to be engaged by such rotary contact in one of such switch positions. A knob member is mounted outside of the connector member on the outer conductor and is connected to the rotary contact by a connecting pin extending through such outer conductor for rotating such rotary contact into the different switch positions in order to change the electrical connections of the inner conductor of such coaxial cable transmission line.

2

It is therefore one object of the present invention to provide an improved electrical connector and switch device.

Another object of the invention is to provide an improved electrical transmission line connector and switch device having low inductance and capacitance so that such device transmits an electrical input signal without substantial distortion.

A further object of the present invention is to provide an improved coaxial cable connector and switch device of simple and inexpensive construction so that both the connector and switch are integrally formed in a single device.

Still another object of the present invention is to provide a coaxial cable connector and switch device which requires little wiring time and fewer soldered connections and allows shorter lead lengths so that such device has a more reliable operation and better high frequency characteristics.

An additional object of the present invention is to provide an improved coaxial cable connector and switch device for mounting on the control panel of an electrical apparatus, such as a cathode ray oscilloscope, and having an integral construction to save mounting space on such front panel.

A still further object of the present invention is to provide an improved coaxial cable connector and switch device for use as the input terminal for the vertical preamplifier of the cathode ray oscilloscope so that such input terminal can be switched between an A.C. input signal position, a D.C. input signal position and a ground position by rotation of a knob member in such device.

Other objects and advantages of the present invention will become apparent after referring to the following detailed description of a preferred embodiment thereof and to the attached drawings of which:

FIG. 1 is a perspective view of the front of one embodiment of the electrical connector and switch device of the present invention;

FIG. 2 is a vertical section taken along the line 2—2 of FIG. 1;

FIG. 3 is a rear end view of FIG. 2;

FIG. 4 is a vertical section view taken along the line 4—4 of FIG. 2;

FIG. 5 is a vertical sectional view taken along the line 5—5 of FIG. 2;

FIG. 6 is an exploded perspective view of one embodiment of the switch contacts of the device of FIG. 1 for a two-position switch; and

FIG. 7 is an exploded perspective view of another embodiment of the switch contacts of the device of FIG. 1 for a three-position switch.

The electrical connector and switch device of the present invention shown in FIGS. 1 and 2 includes a coaxial cable connector 10 and a two-position rotary switch 12 formed integral with such connector. The connector 10 includes a cylindrical rod inner conductor 14 and a hollow tubular outer conductor including a first outer conductor member 16 and a second outer conductor member 18 which are coaxially mounted with the inner conductor so that such inner conductor is spaced from such outer conductor by a pair of tubular insulating members 20 and 21. The first outer conductor member 16 has a web flange portion 22 extending radially outward on the exterior surface of such conductor member between the two ends of such conductor member. The large diameter end of outer conductor member 16 is adapted to be connected to the outer conductor of a coaxial cable transmission line (not shown) by means of external screw threads 24 and the small diameter end of such member is also provided with external screw threads 25 for attachment to the second

outer conductor member 18. The inner conductor 14 has an enlarged connector end 26 in the form of a cylindrical plug receptacle which is split into several spring finger portions that engage the central signal-carrying conductor of the coaxial cable. The connector end 26 of the inner conductor fits inside a passage way in the insulator member 20 which is held in place within the first outer conductor member 16 by a retaining ring 28 seated in a notch in the inner surface of such outer conductor member and the internal shoulder of flange 22. The inner conductor 14 is also held in place by a knurled portion 30 that engages the inner surface of the insulating member 21 which is secured inside the first outer conductor member 16 by a rolled edge 32 of reduced diameter on the small end of such member. The second outer conductor member 18 is attached to the first outer conductor member 16 by internal screw threads 34 on the small diameter end portion of such member which engages the external screw threads 25 on such first outer conductor member. The larger diameter end portion of the second outer conductor member 18 is adapted to be attached to a mounting surface, such as the control panel of a cathode ray oscilloscope, by means of external screw threads 36 and a flat key surface 37. An intermediate web flange portion 38 is also provided between the large and small diameter end portions of such member.

The rotary switch 12 includes a cylindrical knob member 40 which is mounted between the flange portions 22 and 38 of the outer conductor members so that it rotates about such conductor members but is prevented from longitudinal movement with respect to such conductor members by such flange portions. This knob member is suitably secured to a knob insert 42, such as by an epoxy resin adhesive, so that the inner surface of such knob insert slides on the outer surface of the small diameter end portion of the second outer conductor member 18. The knob member 40 may be made of plastic material with a suitable switch position pointer or index 44 located on the front end of such knob member where it can be seen by the operator. A rotary switch contact support plate 46 of insulating material is connected to knob member 40 by means of a connecting pin 48 which is secured inside a cavity in the rear end of the knob insert 42 by adhesive or other suitable means and extends through an arcuate slot 50 in the web flange 38 into a passageway in the support plate 46. As shown in FIG. 6, a rotary switch contact 52 in the form of a leaf spring is secured to the inner conductor 14 by a pair of spring fingers 54 which engage the inner conductor in all switch positions so that such rotary contact is always electrically connected to such inner conductor. The rotary contact 52 is keyed to the support plate 46 by a pair of stops 56 at one end of such plate positioned on either side of the contact end of such rotary contact so that both the support plate and the rotary contact rotate together about the inner conductor 14 when the knob member 40 is turned between two switch positions for A.C. or D.C. connection of said inner conductor.

The A.C. and D.C. switch positions are determined by a detent mechanism mounted in a cavity in the rear end knob insert 42. This detent mechanism includes a ball bearing detent 58 positioned on top of a coiled detent spring 60 so that such detent engages one of two detent notches 62 and 64 circumferentially spaced in the outer surface of the web flange 38 of the second outer conductor member 18. The rotary switch contact 54 is positioned adjacent a stationary switch contact support plate 68 of insulating material which is provided with a stationary switch contact 70 in the form of a rivet. The stationary contact 70 extends through a tapered hole in switch plate 68 so that it is held by a friction fit and the head of said stationary contact is in position to be engaged by the rotary contact 52 in one of the two switch positions. A pair of guide ramp portions 72 extend from the opposite sides of the rotary contact 52 to guide the stationary con-

tact up onto such rotary contact during the switching operation. The stationary support plate 68 is mounted on the inner conductor rod 14 against an annular shoulder on the inside surface of the large diameter end of outer conductor member 18 and is held in position by a retaining ring 74 which is seated in a radial notch in the interior surface of such end of such outer conductor member. This retaining ring 74 is keyed to the outer conductor member 18 and the stationary switch plate 68 by a key portion 75 which engages a keyway slot in such member and is positioned between a pair of raised projections 77 on the surface of the plate to prevent the rotation of such plate, as shown by the rear view of FIG. 3.

The inner conductor 14 of the connector and switch device of the present invention may be connected through a blocking capacitor 76 to the vertical preamplifier of the cathode ray oscilloscope in the A.C. switch position. The stationary switch contact 70 is connected to short-circuit this blocking capacitor 76 when such stationary contact engages the rotary contact 52 so that it corresponds to the D.C. switch position.

The two switch positions of the rotary switch including knob member 40 are shown clearly in FIGURE 5. The furthest clockwise first switch position of the knob member 40 corresponds to the position 48A of the connecting pin 48 in the slot 50 through web flange 38 of the second outer conductor member 18, when the ball detent 58 is in the detent notch 62. This first switch position corresponds to the D.C. position in which the blocking capacitor 76 is short-circuited by rotary contact 52 engaging stationary contact 70. The furthest counter-clockwise second switch position corresponds to the position 48B of the connecting pin when the detent 58 engages detent notch 64 so that the rotary contact 52 is positioned in contact with the insulator surface of stationary support plate 68 remote from the stationary contact 70. This second switch position corresponds to the A.C. position when the signal transmitted through the inner conductor 14 must be transmitted through the D.C. blocking capacitor 76.

As shown in FIG. 7, the rotary switch 12 of the connector and switch device of FIG. 1 may be provided with a third switch position in which the inner conductor 14 is disconnected and the input lead to the vertical preamplifier is connected to ground. This ground switch position may be employed when calibrating the vertical preamplifier of the oscilloscope. However, it is not possible to do this merely by providing a second stationary switch contact which is grounded since this would change the input impedance of the preamplifier by connecting it to ground through the blocking capacitor. Instead, four stationary contacts 70', 78, 80 and 82 are secured to the stationary support plate 68' in radially spaced, insulated relationship. The first stationary contact 78 is connected to the inner conductor 14 by a metal coating 84 on the rear surface of support plate 68'. The second stationary contact 80 is connected through blocking capacitor 76 to the vertical preamplifier, while the third stationary contact 70' is connected directly to such preamplifier without passing through such capacitor. Fourth stationary contact 82 is connected to ground through another metal coating 86 on the rear surface of support plate 68', which extends around the periphery of such plate so that it is in contact with the second outer conductor member 18. These metal coatings 84 and 86 on support plate 68' may be formed in the manner of a printed circuit.

The rotary switch contact member 52' of FIG. 7 is provided with three separate spring contacts 88, 90 and 92 which are made from a single piece of metal so they are interconnected by a common support portion 94. This rotary contact member 52' is mounted on a rotary support plate 46' of insulating material with the common support portion 94 positioned in an arcuate groove 96 in the rear surface of such plate so that the three rotary contacts 88, 90 and 92 are seated in three separate

notches 98, 100 and 102, respectively, adjacent such groove. The rotary support plate 46' is pivoted about the inner conductor 14 by the connecting pin 48 when the switch knob 40 is rotated between three switch positions corresponding to stationary contacts 70', 80 and 82. 5 Obviously a third detent notch (not shown), in addition to detent notches 62 and 64, must be provided in order to allow three switch positions. Thus, in the A.C. switch position rotary contacts 90 and 92 engage the head ends of stationary contacts 78 and 80, respectively, to interconnect these first and second stationary contacts so that the input signal in the inner conductor flows through D.C. blocking capacitor 76. In the D.C. switch position the rotary contacts 88, 90 and 92, engage stationary contacts 78, 80 and 70, respectively, to interconnect the first and 10 third stationary contacts so that the input signal can flow directly to the vertical preamplifier without passing through the blocking capacitor. Finally, in the ground switch position the rotary contacts 88, 90 and 92 engage the stationary contacts 80, 70' and 82, respectively, to interconnect the third and fourth stationary contacts so that the input of the preamplifier is directly grounded and is disconnected from the input signal in inner conductor 14. The blocking capacitor 76 is short-circuited in the 15 D.C. and ground switch positions to prevent charging of such capacitor and to insure that such a charge signal is not added to the input signal transmitted when the switch is rotated to the next A.C. position.

It will be obvious that various changes may be made in the details of the preferred embodiment of the present 30 invention. For example, the coaxial cable connector 10 may be provided with a conventional BNC bayonet-type connector, instead of the screw-type U.H.F. connector shown, for attachment to the coaxial cable while the first and second outer conductor members 16 and 18 may be formed as an integral piece if one of the flange portions is replaced by a retaining ring in order to enable mounting of the knob member and knob insert. Also, any number of switch positions may be employed with a corresponding increase or decrease in the number of stationary 35 switch contacts. Therefore, it is not intended to limit the scope of the present invention to the above-described preferred embodiments thereof and such scope should only be determined by the following claims.

I claim:

1. An electrical connector and switch device for changing the connections to a transmission line comprising: 40 a connector member including an inner signal-carrying conductor and an outer shield conductor, having one end adapted to be connected to said transmission line; a movable switch member including a movable switch contact, mounted inside said connector member at its other end for movement between a plurality of different switch positions; a stationary switch member including at least one stationary switch contact, mounted inside said shield conductor so that said stationary contact is positioned to be engaged by said movable contact in at least one of said switch positions; and means mounted outside said connector member and extending through the side of said shield conductor for moving said movable switch member into said different switch positions in order to change the electrical connection of said transmission line without substantially distorting in said connector and switch device the electrical signal supplied by said transmission line. 50

2. An electrical connector and switch device for connecting a transmission line to electrical apparatus in several different ways, comprising:

a connector member including an inner signal-carrying conductor and an outer shield conductor, in the form of a transmission line section having one end adapted to be connected to said transmission line; 55

6 a movable switch member including a movable switch contact, mounted inside said connector member at its other end for movement about said signal conductor between a plurality of different switch positions;

a stationary switch member including at least one stationary switch contact, mounted inside said shield conductor so that said stationary contact is positioned to be engaged by said moveable contact in at least one of said switch positions; and

knob means mounted outside said connector member and extending through a slot in the side of said shield conductor for moving said movable switch member into said different switch positions in order to change the electrical connection of said transmission line to said apparatus without substantially distorting in said connector and switch device the input signal supplied by said transmission line.

3. An electrical connector and switch device for connecting a transmission line to electrical apparatus in several different ways, comprising:

a connector member including an inner signal carrying conductor and an outer shield conductor, in the form of a transmission line section having one end of both of said conductors adapted to be connected to said transmission line;

a rotatable switch member including a rotary switch contact, mounted inside said shield conductor at its other end for rotation about said signal conductor between a plurality of different switch positions;

a stationary switch member including at least one stationary switch contact, mounted inside said shield conductor so that said stationary contact is insulated from said shield conductor and is positioned to be engaged by said rotary contact in at least one of said switch positions; and

knob means rotably mounted on the outside of said shield conductor for rotation about said shield conductor, said knob means having a coupling element extending through the side of said shield conductor for rotating said rotary switch member into said different switch positions in order to change the electrical connection of said transmission line to said apparatus without substantially distorting in said connector and switch device the input signal supplied by said transmission line.

4. An electrical connector and rotary switch device for connecting a coaxial cable transmission line to electrical apparatus in several different ways, comprising:

a connector member including a cylindrical inner signal carrying conductor and a tubular outer ground conductor, in the form of a coaxial cable transmission line section having one end of both of said conductors adapted to be connected to said transmission line;

a rotatable switch plate having a movable switch contact attached thereto, mounted inside said ground conductor at its other end for rotation on said signal conductor between a plurality of different switch positions while said rotary contact engages said signal conductor;

a stationary switch plate, at least one stationary switch contact attached thereto, mounted inside said ground conductor so that said stationary contact is insulated from said ground conductor and said signal conductor and is positioned to be engaged by said rotary contact in one of said switch positions; and

knob means including a knob member rotably mounted on the outside surface of said ground conductor for rotation about said ground conductor and a coupling member extending through a slot in the side of said ground conductor and attached to both said rotatable switch plate and said knob member, for rotating said rotary switch member into said different switch positions by rotation of said coupling

member about said signal conductor in order to change the electrical connection of said transmission line to said apparatus without substantially distorting in said connector and switch device the input signal supplied by said transmission line.

5. An electrical connector and switch device for connecting a transmission line to electrical apparatus in several different ways, comprising:

a tubular outer conductor having one end adapted to be connected to said transmission line and its other end adapted to be attached to said apparatus, and having a pair of spaced flange portions on the exterior surface between the ends of said outer conductor;

a cylindrical inner conductor mounted inside said outer conductor so that it is insulated from said outer conductor, having one end adapted to be connected to said transmission line and another end adapted to be connected to said apparatus;

a rotary switch contact mounted for rotation about said inner conductor inside said outer conductor, while said rotary contact is in engagement with said inner conductor, between a plurality of switch positions;

a stationary switch contact fixedly mounted inside said outer conductor so that it is insulated from said inner conductor and said outer conductor and is positioned to engage said rotary switch contact in one of said switch positions;

a knob member mounted for rotation about said outer conductor and positioned between said flange portions on the exterior of said outer conductor to prevent longitudinal movement of said knob member; and

a connecting element extending through said outer conductor inside a slot in one of said flange portions and attached at one end to said knob member outside said outer conductor and at its other end to said rotary switch contact inside said outer conductor in order to connect said knob member with said rotary contact so that they rotate together.

6. An electrical connector and switch device for connecting a coaxial cable transmission line to electrical apparatus in several different ways, comprising:

a tubular outer conductor having one end adapted to be connected to said coaxial cable and its other end adapted to be attached to said apparatus and having a pair of spaced flange portions extending outwardly on the exterior surface between the ends of said outer conductor;

a cylindrical inner conductor coaxially mounted inside said outer conductor so that it is spaced from said outer conductor by insulating material, having one end adapted to be connected to said coaxial cable and another end adapted to be connected to said apparatus;

a rotary switch member including a rotary switch contact mounted for rotation about said inner conductor inside said outer conductor, while said rotary contact is in engagement with said inner conductor, between a plurality of switch positions;

a stationary switch member including at least one stationary switch contact fixedly mounted inside said outer conductor so that it is spaced from said inner conductor and said outer conductor by insulating material, and is positioned to engage said rotary switch contact in one of said switch positions;

a knob member mounted for rotation about said outer conductor and positioned between said flange portions on the exterior of said outer conductor to prevent longitudinal movement of said knob;

a detent member mounted on said knob member adjacent one of said flange portions and positioned so that said detent member will engage a plurality of spaced detent notches in the outer surface of said one flange portion in order to determine said switch positions; and

a connecting pin extending through said outer conductor inside a radial slot in said one flange portion and attached to one end to said knob member outside said outer conductor and at its other end to said rotary switch contact inside said outer conductor in order to connect said knob member with said rotary contact so that they rotate together.

7. An electrical connector and switch device for connecting a coaxial cable transmission line to a cathode ray oscilloscope in several different ways, comprising:

a tubular first outer conductor member having one end adapted to be connected to said coaxial cable and its other end adapted to be attached to another outer conductor member, and having a first flange portion on the exterior surface between the ends of said first outer conductor;

a tubular second outer conductor member having one end attached to said other end of said first outer conductor and its other end adapted to be secured to said oscilloscope, and having a second flange portion on the exterior surface between the ends of said second outer conductor;

a cylindrical inner conductor coaxially mounted inside said first and second outer conductor members so that it is insulated from said outer conductor members, having one end adapted to be connected to said coaxial cable and another end adapted to be connected to said oscilloscope;

a rotary switch contact member including a plurality of separate, interconnected rotary contacts, mounted for rotation about said inner conductor inside said second outer conductor member while insulated from said outer conductor members and said inner conductor, between a plurality of switch positions;

a plurality of stationary switch contacts fixedly mounted inside said second outer conductor member so that said stationary contacts are insulated from each other and are each positioned to engage one of said rotary contacts in one of said switch positions to interconnect said stationary contacts, with one of said stationary contacts being connected to ground and another connected to said inner conductor;

a knob member mounted for rotation about said outer conductor members outside thereof and positioned between said first flange portion and said second flange portion to prevent longitudinal movement of said knob with respect to said conductor members;

a spring biased detent member mounted on said knob member adjacent said second flange portion and positioned so that said detent member will engage a plurality of circumferentially spaced detent notches in the outer surface of said second flange portion in order to determine said switch positions; and

a connecting pin extending through said second outer conductor member inside a radial slot through said second flange portion and attached to said knob member to said rotary switch contact in order to connect said knob member with said rotary switch contact so that they rotate together.

8. An electrical connector and switch device for connecting a coaxial cable transmission line to a cathode ray oscilloscope in several different ways, comprising:

a cylindrical first outer ground conductor member of circular cross-section having one end adapted to be connected to said coaxial cable and its other end adapted to be attached to another outer conductor member, and having a first web flange portion on the exterior surface between the ends of said first outer conductor;

a tubular second outer ground conductor member of circular cross-section having one end attached to said other end of said first outer conductor and its larger other end adapted to be secured to said oscilloscope, and having a second web flange portion on the exterior surface between the ends of said second outer conductor;

- a cylindrical inner signal carrying conductor coaxially mounted inside said first and second outer conductor members so that it is spaced from said outer conductor members by insulating material, having one end adapted to be connected to said coaxial cable and another end adapted to be connected to said oscilloscope; 5
- a rotary switch member including a rotary switch contact, mounted for rotation about said inner conductor inside said larger end of said second outer conductor member in between a plurality of switch positions while said rotary contact is in engagement with said inner conductor; 10
- a stationary switch member including a pair of spaced stationary switch contacts, fixedly mounted inside said larger end of second outer conductor member so that said stationary contacts are spaced from said inner conductor and said outer conductor members by insulating material, and are each positioned to engage said rotary switch contact in one of said switch positions; 15
- a knob mounted for rotation about said outer conductor members outside thereof and positioned between said first flange portion and said second flange portion to prevent longitudinal movement of said knob with respect to said outer conductor members; 20
- a spring biased detent member mounted inside a cavity in the surface of said knob adjacent said second flange portion and positioned so that said detent member will engage a plurality of circumferentially spaced detent notches in the outer surface of said second flange portion in order to determine said switch positions; and 25
- a connecting pin attached to said knob, extending through said second outer conductor member inside a radial slot through said second flange portion and 30
- 35

- attached to said rotary switch contact inside said second outer conductor member in order to connect said knob with said rotary switch contact so that they rotate together.
9. An electrical connector and switch device for connecting a transmission line to electrical apparatus in several different ways, comprising:
- a tubular outer conductor having one end adapted to be connected to said transmission line and its other end adapted to be attached to said apparatus; an inner conductor mounted inside and said outer conductor so that it is insulated from said outer conductor, and having one end adapted to be connected to said transmission line and another end adapted to be connected to said apparatus;
- a rotary switch contact mounted for rotation about said inner conductor inside said outer conductor between a plurality of switch positions;
- a stationary switch contact fixedly mounted inside said outer conductor so that it is positioned to engage said rotary switch contact in one of said switch positions;
- a knob member mounted for rotation about said outer conductor; and
- a connecting rod extending through the side of said outer conductor inside a slot in said outer conductor and attached at one end of said knob member outside said outer conductor and at its other end of said rotary switch contact inside said outer conductor in order to connect said knob member with said rotary contact so that they rotate together.
